3 Claims. (Cl. 60—39.65)

The present invention relates to an improved inner liner for combustion systems and more particularly to a cowled dome liner for a higher combustion intensity, straight through, combustion system of the type usually associated with gas turbine engines.

In cannular type combustion systems it has been common practice to provide cross tubes between adjacent liners so that cross ignition occurs permitting essentially instantaneous combustion in all liners. In addition, secondary air is directed around the dome of the liners and mixed with the products of combustion to quench the hot gases. One of the major problems in this type combustion system has been the tendency of the liners to buckle and crack around the cross tubes and in the dome region surrounding the primary combustion zone, thus reducing the average liner life. This problem has its origin in the fact that as the secondary air flows around the cross tubes decreased static pressures are created in that vicinity according to Bernoulli's Theorem. The lower static pressures cause decreased air penetration into the liner around the cross tubes and often result in flame being forced out of the liner into the secondary air passage. Therefore, the cross tubes in the past always tended to run hot around the attachment to the liner. This periodic heating and subsequent cooling produced expansion and contraction of the cross tubes which caused fatigue and eventual failure in the metal of the liner resulting in the formation of large holes at the point of attachment of the cross tubes to the liner. In addition, the decreased penetration of the cooling air over certain areas of the dome caused these areas to become hotter than the remainder of the dome, thus developing internal stresses which resulted in buckling and cracking of the dome.

The present invention overcomes the disadvantages of the prior known devices and increases the average liner life by removing the thermal stresses from the hot metal of the liner and insuring uniform air penetration into the primary combustion zone of the liner resulting in more uniform combustion and consequently more uniform temperature on the dome. This is accomplished in the present invention by provision of a cowl extending around the entire primary combustion zone which acts as a plenum chamber to equalize the pressure and flow of primary air throughout the primary zone. The leading edge or snout of the cowl extends upstream into the diffuser to receive primary air having a relatively good velocity profile, thus assuring a proper distribution of air on all sides of the liner. The cross tubes are attached to the cowl and extend through an opening in the liner into the primary combustion zone, the edges of the opening making sliding contact with the cross tubes. A transition wall connects the primary and secondary zones of the liner and adds rigidity and strength to the liner. This transition wall is cooled by a film of air from the cowl which prevents burning of the transition section.

An object of the present invention is the provision of means for extending the average life of an inner liner in

a high temperature, straight through combustion system.

Another object of the present invention is the provision of an improved inner liner for a combustion system which permits uniform air distribution over the dome region and uniform air penetration into the primary combustion zone.

A further object is the provision of an improved inner liner for a combustion system which provides stable and efficient combustion and uniform turbine inlet temperature distribution.

Other objects and many of the attendant advantages of this invention will be readily appreciated as the same becomes better understood by reference to the following detailed description when considered in connection with the accompanying drawings wherein:

Fig. 1 is an elevation view in longitudinal section of a cowled dome liner according to the present invention;

Fig. 2 is a sectional view at an enlarged scale of the transition section between the primary and secondary zone of the present invention; and

Fig. 3 is a sectional view taken along line 3—3 of Fig. 1.

Referring more particularly to Fig. 1 of the drawing, the improved inner liner shown therein consists in essence of a dome 11 which defines the primary combustion zone, a secondary or mixing section 12, a transition wall 13 between the dome and the secondary region, and a cowl 14 surrounding the dome. A fuel nozzle 15 is received within the opening 16 at the apex of the dome 11. A plurality of openings are provided in the wall of the liner surrounding the primary combustion zone and are arranged in three bands 17, 18, and 19 about the periphery of the liner. Louvres 21 are positioned in the wall of the liner between adjacent openings of the bands 17, 18, and 19. In addition, other louvres such as 22 are so positioned in the dome to insure effective air penetration over the entire area of the dome. The secondary region 12 is a generally cylindrical section having a number of bands of openings 23 positioned in the walls thereof. As in the dome region, the louvres 24 are interspersed between adjacent openings of some of the bands 23. The cowl 14 extends around the entire primary combustion zone and is attached at its trailing edge to the secondary portion at the transition section. An opening 25 is formed in the dome to receive the cross tube 26. As illustrated in Fig. 3, the edges of the opening 25 are bent outwardly to form an annular flange 27 which bears against the outside of the cross tube. A similar opening 28 is formed in the cowl opposite the opening 25 in the dome. The edges of the opening 28 are likewise turned outwardly to define an annular flange 29. An angular collar 30 is affixed to the flange 29. A peripheral flange 31 is provided on the exterior of the cross tube and bears against the collar 30. The cross tube is retained within the openings 25 and 28 by means of a clamp (not shown) which locks the flange 31 and the collar 30 together. The leading edge or snout 32 of the cowl is of reduced size and extends upstream into the diffuser 33. The entire liner may be mounted on one wall of the combustion chamber 34 by means of the bracket 35.

The transition wall 13, as shown in Fig. 2, is an annular member having two parallel flanges 36 and 37 joined by an intermediate portion 38. The intermediate portion is perforated as at 39 at close intervals near the flange 36. The trailing edge 41 of the dome is bent outwardly as shown, overlying the perforations 39 and defining an annular slot 42 which opens outwardly away from the dome.

In the operation of the present device the leading edge or snout of the cowl extending upstream into the diffuser,

receives primary air before a poor velocity profile can develop. This primary air is directed into the plenum chamber formed by the cowl, the dome and the transition wall. A uniform positive static pressure is thus produced around the entire primary combustion zone forcing the primary air through the louvres and the bands of openings. This uniform positive pressure assures uniform air penetration over the entire dome which results in uniform combustion throughout the primary combustion zone. The uniform combustion results in stable continuous burning, thus heating the entire dome evenly and causing uniform turbine inlet temperature distribution. The air from the diffuser 33 which is not picked off by the leading edge of the cowl becomes cooling or secondary air and flows around on the outside of the cowl and then through the openings 23 and the louvres 24 into the secondary region 12 where it mixes with and quenches the hot gases from the primary combustion zone. Primary air, in addition to being forced into the primary combustion zone, is discharged through the perforations 39 in the transition wall into the annular slot 42 and thence out into the secondary region. The air from the perforations fills the annular slot and then flows out over the upturned edge 41, forming a film of cooling air over the intermediate member 38 and the flange 37 of the transition wall. The combustion gases flowing from the primary combustion zone into the secondary region form a vortex at the point of discharge from the combustion zone, creating an additional flame holder at this point and thereby burning the liquid fuel in the cooling boundary air film from the primary zone, resulting in an increase in combustion efficiency. The film of cooling air over the intermediate portion and the rearward flange prevents destruction of the transition wall by the flame holding in this region. The remainder of the liner is cooled by the primary or secondary air which enters through the louvres 21, 22, and 24 and forms a thin film over the interior of the liner. A cross tube 26 is received in the opening 28 and secured to the cowl 14, such that it extends through the opening 25 into the primary combustion zone. Since the cross tube is secured to the cowl and makes only sliding contact with the flange 27 of the dome, any stresses caused by the periodic heating and subsequent cooling of the cross tube are transmitted to the relatively cool cowl instead of to the intensely hot dome. Since the cowl is relatively cool it is much more resistant to fatigue from the oscillations caused by the temperature changes in the cross tubes, and has a much longer life under these conditions than would the dome which is subjected to intense heat.

While a particular embodiment of the invention has been illustrated and described, it will be obvious to those skilled in the art that various changes and modifications may be made without departing from the invention and it is intended to cover in the appended claims all such changes and modifications that come within the true spirit and scope of the invention.

What is claimed is:

1. For use in a combustion system including a combustion chamber and a diffuser, a cowled dome liner

adapted to be positioned in said chamber, said liner comprising: a dome section defining the primary combustion zone, said dome having a plurality of openings therein; a cowl spaced from and surrounding the dome, said cowl having a protruding snout portion extending upstream into the diffuser to receive primary air having a good velocity profile; an annular wall extending between the dome and the cowl, the space bounded by the dome, the annular wall and the cowl forming a plenum chamber for the equalization of primary air pressure over the entire outer surface of the dome; a mixing section having a larger diameter than said dome, said mixing section being connected to said cowl; and means carried by the dome for directing cooling air across the wall to prevent burning thereof.

2. For use in a combustion system including a combustion chamber and a diffuser, a cowled dome liner adapted to be positioned in said chamber, said liner comprising: a dome section defining the primary combustion zone, said dome having a plurality of openings therein; a cowl spaced from and surrounding the dome, said cowl having a protruding snout portion extending upstream into the diffuser to receive primary air having a good velocity profile; an annular wall extending between the dome and the cowl, the space between the dome, the annular wall and the cowl forming a plenum chamber for the equalization of primary air pressure over the entire outer surface of the dome; a mixing section having a larger diameter than said dome, said mixing section being connected to said cowl; and means carried by the dome for directing cooling air across the wall to prevent burning thereof.

3. A cowled dome liner for use in a combustion system comprising: a dome section defining the primary combustion zone; a cowl surrounding the entire dome, said cowl being spaced from the dome to provide a plenum chamber therebetween, means on said cowl supplying primary air having a good velocity profile to said plenum chamber; a mixing section connected to the cowl; an annular wall forming the downstream end of the plenum chamber, said wall including an intermediate portion spanning the distance between the dome and the mixing section; and cooling means to prevent burning of the wall, said cooling means including a plurality of openings in the intermediate portion and an annular slot formed by the intermediate portion and the trailing edge of the dome.
